UNITED STATES PATENT OFFICE.

FRANK H. STANWOOD, OF WILMETTE, ILLINOIS, ASSIGNOR TO STANWOOD EQUIPMENT COMPANY, OF CHICAGO, ILLINOIS, A CORPORATION OF MAINE.

DESIGN FOR A STEP PLATE.

60,885.

Specification for Design. Patented Apr. 18, 1922.

Application filed February 21, 1921. Serial No. 446,964. Term of patent 7 years.

To all whom it may concern:

Be it known that I, FRANK H. STANWOOD, a citizen of the United States, residing at Wilmette, in the county of Cook and State of Illinois, have invented a new, original, and ornamental Design for Step Plates, of which the following is a specification, reference being had to the accompanying drawing, forming a part thereof.

On the drawing, the figure is a top plan view of a step plate embodying the design.

I claim:

The ornamental design for a step plate, as shown.

FRANK H. STANWOOD.
